(57) **CLAIM**

The ornamental design for a cap for reusable bottle, as shown and described.

DESCRIPTION

FIG. 1 is a perspective view illustrating a design for a cap for a reusable bottle.

FIG. 2 is a top view of the cap of FIG. 1.

FIG. 3 is a back elevation view of the cap of FIG. 1.

FIG. 4 is a front elevation view of the cap of FIG. 1.

FIG. 5 is a left elevation view of the cap of FIG. 1.

FIG. 6 is a right elevation view of the cap of FIG. 1; and,

FIG. 7 is a bottom view of the cap of FIG. 1.

The dashed lines in the figures are for environmental purposes only and form no part of the claimed design.
